tion from one side of the siphon to the other, this advantage not being obtainable in prior art forms of flat body type siphons.

It will of course be understood that various changes in details of construction and arrangement of parts may be made by those skilled in the art without departing from the spirit of the invention as set forth in the appended claims.

I claim:

1. In combination, a fire box having a crown sheet and front water leg, and a siphon formed of a relatively large body having an inlet neck at its lower part communicating with said front water leg and having a plurality of outlet necks at its upper part for connection to the crown sheet, said body portion having a lowermost wall which curves upwardly to form the back end of the siphon while the top of said inlet neck

5 curves in a reverse direction toward the front of the fire box and then curves upwardly to form the front edge of the siphon, and at least certain of said outlet necks being of tubular formation and including said front and rear edges of the siphon.

2. In combination a fire box box having a crown sheet and front water leg, and a siphon formed of a relatively large body having an inlet neck at its lower part communicating with said front water leg and having a plurality of outlet necks at its upper part for connection to the crown sheet, said outlet necks being substantially of tubular formation spaced from each other and joined together at their lower ends by walls which are curved in both longitudinal and transverse planes.

THOMAS H. FAWCETT.
